DISCONNECTING HOLDER

Leroy C. Doane, Meriden, Conn., assignor to The Miller Company, Meriden, Conn., a corporation of Connecticut

Application January 20, 1930, Serial No. 422,005

13 Claims. (Cl. 173—328)

The present invention relates to disconnecting holders and is more particularly directed toward a polarity connector for lighting apparatus and the like.

5 The present invention contemplates a disconnecting holder more particularly arranged for lighting apparatus and adapted to support the lamp socket and shade or reflector in such a manner that the polarity of the lamp socket terminals is maintained the same in all such fixtures and is not changed when the lamp socket and associated parts are removed from the fixed parts and again replaced.

10 The invention also contemplates an arrangement of parts whereby the lamp socket and associated shade or reflector or other device may be connected and disconnected by a simple operation which insures predetermined polarity of the lamp socket, or other load connectible device.

15 The accompanying drawing shows, for purposes of illustrating the present invention, one of the many embodiments in which it may take form, it being understood that the drawing is illustrative of the invention rather than limiting the same.

In the drawing:

Figure 1 is a vertical sectional view through the fixed part of the disconnecting holder, this figure being taken on the line 1—1 of Figure 2 in the direction of the arrow;

Figure 2 is an inverted plan view of the same;

Figure 3 is a vertical sectional view through the disconnecting holder; and

Figure 4 is a top plan view showing the removable socket carrier.

The fixed supporting body is shown at 10. It may be in the form of a casting and may be internally threaded, as indicated at 11, to facilitate mounting it on the lower end of a pipe or the like. The lower part of the casting 10 is in the form of a circular skirt 12, provided with internally disposed helical ledges 13. These ledges, at their lower portions, terminate near slots 14, 15, and 16, and the upper and more remote parts of the ledges are provided with dwells or recesses 17.

An insulating body 20 is secured to the holder 10 by screws indicated at 21, the holes into which these screws pass having predetermined positions relative to the notches 14, 15 and 16. The insulating body 20 carries two metal plates 22 and 23 having binding screws 24 and 25, and adapted to receive the lead in wires for the fixture. One of these terminals may be marked G, as indicated, to indicate that it is to be connected to

the grounded side or to the negative side of the circuit. Each of these terminals 22 and 23 has a downwardly extending portion such as indicated at 26, and these downwardly extending portions 26 yieldably carry contact terminals 27 and 28. These terminals are housed in depending portions 29 of the insulating body.

A conventional lamp socket is shown at 30. It is preferably mounted on a shock absorbing socket support 31 of the character shown in Patent No. 1,788,945, granted June 13, 1931. This shock absorber is secured by rivets 32 to a cup shaped stamping 33 and allows the socket to move relative to its support. This stamping is apertured, as indicated at 34, to accommodate an insulating body 35 which surrounds two rearwardly extending blades 36 and 37 carried by the lamp socket. These blades are tapped to receive screws 38 and 39 and these screws are tightened in place as indicated.

20 A cup shaped stamping 33 is secured inside a socket cover and reflector support 40 by pins indicated at 41, 42 and 43. These pins are preferably in the form of large headed screws which pass through nuts 44 and are upset as indicated at 45. 25 The screws 41, 42 and 43 are spaced the same as the notches 14, 15, and 16 and one of these screws, for example the screw 41, is made larger than the others. The corresponding notch 14 is made larger and, hence, it would be impossible 30 to insert the disconnectible part of the holder in any other position than that in which the screw head 41 passes through the notch 14.

When the lower part of the unit is thus passed into place, the upper edge of the lower disconnectible part is brought against a fibre washer 46 placed underneath a spring 47 and above a flange 48 on the insulating support 20. This compresses the spring 47. One may then turn the lower part of the unit about a quarter revolution to pass the heads of the screws 41, 42, and 43 into the recesses or dwells 17 in the ledges 13. This movement will bring the heads of the screws 38 and 39 against the terminals 27 and 28 of the first part of the holder, thereby completing the circuit. 45

It will be noted that, when connected, the holder must always have the proper polarity. Large conducting parts may be employed, and large surfaces are available, so that good contact may be had at all times. Furthermore, the resiliently 50 mounted fixed contacts 27 and 28 are able to give sufficiently to permit the shock absorbing support for the lamp socket to function and protect the lamp.

The socket cover 40 may have any of the usual 55

configurations employed for supporting metal or other reflectors, or various shade supporting devices may be associated with or carried by this socket cover. Where it is desired to have a 5 polarity connection for current consuming devices not employing lamp sockets, it will be obvious that a suitable form of connecting block may be carried by the removable element, so that the desired polarity connections may be made.

10 It is obvious that the invention may be embodied in many forms and constructions, and I wish it to be understood that the particular form shown is but one of the many forms. Various modifications and changes being possible, I do 15 not limit myself in any way with respect thereto.

I claim:

1. A disconnecting connector comprising a fixedly mounted unit having two insulating supported off center contacts and a skirt having 20 ledges provided with dwells to form bayonet joints of predetermined angular relation with the contacts, a socket carrier having pins to co-operate with the ledges and terminals to engage the fixed contacts only when the pins are turned 25 to be received in the dwells in the ledges, whereby the circuit is made or broken during rotary movement of the socket carrier, and spring means carried by the fixedly mounted unit and bearing on the socket carrier for holding the pins in the 30 dwells.

2. A connector comprising an insulating body having two axially extending inwardly facing contacts, the body being open between the contacts to receive a contact carrier, a holder for 35 the insulating body, the holder having a skirted portion, and a removable unit provided with an axially insulating contact carrier receivable between the contacts on the body and carrying downwardly facing contacts engageable with the 40 first mentioned contacts, the outer part of the removable unit being receivable in the skirt, and having pins cooperable with notches and ledges in the skirt to form an asymmetric arrangement of bayonet joints to permit assembly of the parts in 45 predetermined polarity relation.

3. A polarity connection for lighting apparatus comprising a fixed support carrying a pair of insulated contacts adapted to be connected to the line to have a predetermined polarity relation, a 50 lamp socket having its terminals connected to contacts having fixed positions relative to one another, a socket holder, a shock absorber for securing the socket to the socket holder, and means for detachably securing the socket holder to the 55 fixed support, the socket holder and fixed support having registering means to determine the polarity of the socket contacts, the shock absorber protecting the socket against mechanical shock.

4. A connection for lighting apparatus comprising a fixed support carrying a pair of insulated yieldable contacts, a lamp socket having its terminals connected to contacts having fixed positions relative to one another and to the socket, a socket holder and a shock absorber secured to the socket and to the socket holder, the socket holder being detachably carried by the fixed support, the yieldability of the fixed contacts allowing the shock absorber to function without affecting the circuit.

5. A connector comprising a lamp socket unit provided with rearwardly extending terminals, an apertured socket carrier through which the terminals pass, a shock absorber for securing the socket to the carrier, the shock absorber permitting limited movement of the socket unit relative

to the carrier, a fixedly supported insulating body having yieldably supported fixed contacts adapted to receive the rearwardly extending terminals, and means to secure the socket carrier to the support for the insulating body, the fixed contacts yielding to allow the socket unit to move on the shock absorber support therefor.

6. In a disconnecting holder, a supporting body having a depending skirt provided with interiorly disposed notched helical ledges having dwells, an 10 insulating contact support having a pair of spring contacts carried in a downwardly opening axially disposed recess, the contacts being in predetermined angular relation relative to the notches and the notches and dwells being asymmetrically 15 arranged, the insulating support having a peripheral flange, and a spring pressed ring between the flange and the supporting body.

7. In a disconnecting holder, a reflector supporting shell, a cup shaped stamping carried inside the shell, a lamp socket carried below the stamping and having current supply terminals extending above the stamping, and a shock absorber for supporting the socket from the stamping.

8. In a disconnecting holder, a lamp socket having an insulating body and center and screw shell contacts, blade like terminals extending rearwardly from the body and connected to the contacts, a second insulating body to receive the 30 terminals, and lateral extensions carried by the terminals and extending beyond the side walls of the latter body, a third insulating body disposed above the first and having a downwardly opening recess to receive the second insulating 35 body, and terminals carried in the side walls of the recess to contact with the lateral extensions when the parts are in predetermined angular relation.

9. A disconnecting holder comprising a relatively fixed support, an insulating body secured to the lower side of the support, a pair of contact supporting springs carried by the support, contacts carried by the springs and movable radially against the spring tension, a ring slidably and 45 non-removably carried on the insulating body, a spring interposed between the ring and support, and a detachable unit having bayonet slot connections with the support and bearing on the ring to compress the spring when the unit is secured to the support, the unit also carrying an insulating contact carrier having contacts adapted to be brought into engagement with the first contacts when the bayonet slot connections are made up and to flex the spring supports for said contacts.

10. A disconnecting holder comprising a relatively fixed support, an insulating body secured to the lower side of the support, and having a recess on the lower face, a pair of contact supporting springs carried by the support, contacts carried by the springs in the side walls of the recess and movable radially against the spring tension, a ring slidably and non-removably carried on the insulating body, a spring interposed between the ring and support, and a detachable unit having bayonet slot connections with the support and bearing on the ring to compress the spring when the unit is secured to the support, the unit also carrying an insulating contact carrier adapted to enter into the recess and having contacts adapted to be brought into engagement with the first contacts when the bayonet slot connections are made up and to flex the spring supports for said contacts.

11. In a disconnecting holder, an outer tubular socket covering shell, an apertured transverse member fixedly mounted across the shell adjacent the upper end, a shock absorber secured to the lower side of the transverse member, a downwardly opening lamp socket secured to the shock absorber, two current supply contacts secured to the socket and extending up through the aperture in the transverse member and freely movable therein, an insulator about said contacts, the upper ends of the contacts being tapped, and screws extending through holes in the insulator and into the tapped holes, the heads of the screws being exposed.
12. In a disconnecting holder, an outer tubular socket covering shell, an apertured transverse member fixedly mounted across the shell adjacent the upper end, a shock absorber secured to the lower side of the transverse member, a downwardly opening lamp socket secured to the shock absorber, two current supply contacts secured to the socket and extending up through the aperture in the transverse member and freely movable

therein, an insulator about said contacts, the upper ends of the contacts being tapped, and screws extending through holes in the insulator and into the tapped holes, the heads of the screws being exposed.

13. In a disconnecting holder for reflectors, a tubular reflector support having apertures near the upper edge thereof, a cup-shaped member disposed across the upper end of the reflector support, securing members carried by the cup shaped member and projecting beyond and extending through the apertures, the cup shaped member having a central opening, a lamp socket secured to the bottom of the cup shaped member and having terminals extending upwardly through the opening, an insulator slidably received along the terminals and passing through the opening, and insulator securing screws threaded into the contact members and having exposed heads.
